UNITED STATES PATENT OFFICE.

MARTIN EKENBERG, OF STOCKHOLM, SWEDEN, ASSIGNOR TO THE AKTIE-BOLAGET SEPARATOR, OF SAME PLACE.

CENTRIFUGAL MACHINE FOR MIXING GASES WITH LIQUIDS.

SPECIFICATION forming part of Letters Patent No. 542,755, dated July 16, 1895.

Application filed April 13, 1894. Serial No. 507,361. (No model.)

To all whom it may concern:

Be it known that I, MARTIN EKENBERG, a subject of the King of Sweden and Norway, residing at Stockholm, Sweden, have invented 5 a new and useful Improvement in Centrifugal Machines for Mixing Gases with Liquids, of which the following is a specification.

This invention has for its object to produce a centrifugal machine by means of which 10 gases can be intimately mixed with liquids— as, for instance, in aerating and carbonating water and other liquids.

In the accompanying drawings, Figure 1 is 15 a sectional elevation of my improved centrifugal mixing-machine. Fig. 2 is a horizontal section in line 2 2, Fig. 1. Fig. 3 is a sectional elevation showing a slightly-modified construction of the machine. Fig. 4 is a vertical section on line 4 4, Fig. 2.

20 Like letters of reference refer to like parts in the several figures.

A represents the upper disk and B the lower disk of a centrifugal emulsion-machine. b is the upright spindle to which the lower 25 disk is secured and by which it is rotated. The opposing sides of the two disks are made concave or recessed in the usual way, and the recessed portions of the disks are surrounded by marginal faces c and d to hold a sufficient 30 volume of liquid, which are separated by a narrow intervening space or annular slit. The liquid is driven by centrifugal force through this narrow space or slit between the faces of the disks.

35 The upper disk is preferably made adjustable with reference to the lower disk to regulate the width of the intervening space, and the adjusting devices are preferably those which are represented in Figs. 1 and 2, and 40 which are constructed as follows:

The upper portion e of the spindle is enlarged in diameter and provided with a collar f, against the under side of which the lower disk is clamped by a screw-nut g, which is 45 applied to the lower screw-threaded part of the enlarged upper part of the spindle. The upper disk is provided with a hub h, which rests upon a spring i, supported on the collar f, and is pressed down by screw-nuts j, which

are applied to the upper screw-threaded part 50 of the enlarged upper portion of the spindle, so that by tightening the screw-nuts j the upper disk can be adjusted toward and from the lower disk.

The upper portion of the spindle is provided with a bore or cavity k, which opens at the upper end of the spindle and extends downwardly to the level of the collar, where it communicates with one or more lateral passages l, which open through the peripheral 60 face of the collar into the cavity of the lower disk. This bore of the spindle receives the liquid or liquids to be treated from a feed-pipe m, and delivers the same through the passages l into the cavities of the disks. 65

N is a stationary casing or gas-chamber which incloses the disks A and B and which is arranged at a suitable distance therefrom. This casing is supplied with the gas which is desired to be commingled with the liquid. 70 This gas can be conducted to the casing by the pipe n or other suitable means. The casing is fitted tightly around the spindle and the liquid-feed pipe, and is so constructed as to retain the gas and to collect the liquid discharged from the rotating disks. This liquid is preferably removed from the casing by a trapped discharge-pipe o. 75

p represents one or more gas-supply passages formed in one or both of the disks A 80 and B in such manner as to extend from the back or outer surface of the disk to the face or inner surface thereof, so that the gas contained in the gas-chamber can pass through this passage into the space between the disks 85 and become there commingled with the liquid passing outwardly through said space. Each of these gas-passages is preferably provided on the back of the disk with a funnel or mouthpiece p', which opens in the direction 90 in which the disk rotates, and which serves as a gathering device to gather the gas and inject it into the gas-passage, thereby promoting the flow of the gas from the surrounding gas-chamber through said passage into the 95 space between the opposing faces of the disks. The gas which passes through these passages into the space between the disks becomes

thoroughly commingled with the liquid in passing through said space, so that the liquid which is discharged from said space at the peripheries of the disks is an intimate mixture of the liquid and gas.

The gas-supply passages may open at their inner ends in the flat marginal faces of the disks, as shown in Fig. 1, or they may open into annular recesses or mixing-chambers *q*, formed in said faces, as shown in Fig. 3.

The gas-supply passages are preferably curved or inclined outwardly, so that their receiving ends are nearer the axis of rotation than their discharge ends, whereby the centrifugal force is utilized in promoting the flow of the gas through these passages.

While it is desirable in many instances to make provision for adjusting the width of the space between the disks through which the liquid is discharged and in which it is mixed with the gas, this is not indispensable, and the two disks can be rigidly secured together by bolts *r* and intervening stay-pieces *s*, as represented in Fig. 3, or by other suitable means.

The injector funnels or mouthpieces applied to the outer ends of the gas-passages of the disks may be omitted, particularly when the gas in the gas-chamber is under pressure, but they are desirable when the gas-pressure is slight or when the gas is not under pressure—as, for instance, when the machine is used for aerating a liquid—in which case the surrounding casing need not be gas-tight, but may be open to the atmosphere, so as to admit the external air to the disks while serving to collect the aerated liquid which is discharged from the disks.

When the gas which is commingled with the liquid is one which is capable of absorption by the liquid, the effect of the machine is also to bring the liquid in a finely-divided state in contact with the gas and so facilitate the absorption of the gas by the liquid.

It is obvious that two or more liquids can be fed between the disks at the same time for the purpose of commingling the same and at the same time charging the mixture with the gas.

This machine may be used for a variety of purposes, among which may be mentioned the deodorizing of ill-smelling liquid—for instance, liquids containing benzine or carbon

disulphid, and the oxidation of liquids, for instance, in the manufacture of varnish. 55

I claim as my invention—

1. A centrifugal machine for mixing a gas with a liquid consisting of a rotating vessel which is provided with a central inlet for the liquid, a cavity surrounding said inlet and receiving the liquid therefrom, a peripheral discharge extending outwardly from said cavity and through which the mixture of liquid and gas is delivered from the vessel, and with one or more gas supply passages 60 penetrating the wall of said cavity between said liquid inlet and said peripheral discharge, substantially as set forth.

2. A centrifugal machine for mixing a gas with a liquid consisting of a rotating vessel 70 which is provided with a cavity which receives the liquid, with a peripheral discharge extending outwardly from said cavity, and with one or more gas supply passages extending from the outer surface of the vessel into 75 the interior thereof, said gas passages having their inlets arranged nearer the axis of rotation than their outlets, substantially as set forth.

3. A centrifugal machine for mixing a gas 80 with a liquid, consisting of a rotating vessel which is provided with a cavity which receives the liquid, with a peripheral discharge extending outwardly from said cavity, and with one or more gas supply passages extending 85 from the outer surface of the vessel into the interior thereof and provided at their receiving ends with gathering devices, substantially as set forth.

4. The combination with a rotating vessel 90 which is provided with a cavity which receives the liquid, with a peripheral discharge extending outwardly from said cavity and with one or more gas supply passages extending from the outer surface of the vessel into the 95 interior thereof, of a bowl forming a gas supply chamber inclosing said vessel and provided with a gas supply conduit and with a discharge for the liquid, substantially as set forth. 100

Witness my hand this 16th day of March, 1894.

MARTIN EKENBERG.
